CHARLES O. HASKELL, OF HOLLYWOOD, CALIFORNIA.

MEANS AND METHOD OF ELEVATING FLUIDS.

Application filed May 11, 1925. Serial No. 29,520.

This invention relates to means and method of elevating fluids. In particular the invention is adaptable for use in well practice, whether it be water or oil wells, and the invention is adapted to do away with pumping rods of all forms, which rapidly wear out and are unsatisfactory in many particulars. Where a well is pumped by means of pump rods, and if the well must be pumped from a considerable depth, it is very seldom that the casing is exactly true, with the result that the pump rods strike one side of the casing and then the other side and rapidly wear the pump rods, necessitating their replacement within a short time. When it is necessary to replace pump rods, the well must be shut down, and usually five or six days are consumed while new pump rods are being inserted in the well hole. How serious a matter this may be can be realized when it is considered that the average well may produce, say, five hundred barrels of oil a day, and if the well is shut down for six days the production of three thousand barrels of oil has been lost. This amounts to a great deal during the year, as high as thirty-six thousand barrels of oil. This loss of oil of course affects market conditions, and therefore an object of the present invention is to do away with ordinary pumping rods and provide a system which positively elevates the liquid, whether it be oil or water, from any depth in an economical manner. The system and means about to be described has been thoroughly tried out by the inventor and works in a highly satisfactory manner.

The invention has for further objects the provision of an improved system and means for elevating fluids which is superior in point of relative simplicity and inexpensiveness, taken in conjunction with utility, durability and general efficiency and serviceability.

A further object of the invention is the provision of a system and means which cannot be sanded so as to stop its operation.

With the above mentioned and other objects in view, the invention consists in the novel and useful provision, formation, construction, association and relative arrangement of parts, members and features, as well as a method of use, all as shown in certain of its embodiments in the accompanying drawings, described generally and more particularly pointed out in claims.

In the drawings:

Figure 1 is a fragmentary side elevation showing pump means used in practicing the invention, with connections with such pump means and casing and tubing within a well hole;

Figure 2 is a fragmentary vertical sectional view on an enlarged scale, and showing certain of the devices used in practicing the invention;

Figure 3 is a fragmentary cross sectional view detailing certain of the means for preventing a sanding up of certain of the devices, said view being on an enlarged scale from the remaining figures;

Figure 4 is a fragmentary cross sectional view similar to the showing of Figure 2 and showing a slightly modified form of the invention;

Figure 5 is a view similar to Figure 4, showing further details of the invention;

Figure 6 is a horizontal sectional view on the line 6—6 of Figure 2 and,

Figure 7 is a fragmentary cross sectional view of certain means used in practicing the invention, which means is shown in Figure 5, Figure 7 being on an enlarged scale from the showing of said Figure 5.

Corresponding parts in all the figures are designated by the same reference characters.

Referring with particularity to the drawings, the improved means for elevating fluids is designated as an entirety and in one embodiment by A, of which a is a pump, b an air compressor, and means designated generally as c acting in conjunction with the devices a and b for elevating fluid, all of which devices are used in practicing one embodiment of the invention.

Referring to Figure 1 I have illustrated a well bore 1 having a casing 2 within such bore, and which casing is associated with a casing head d at the mouth of such well bore 1. Also concentric within the casing 2 is a delivery tube 3 which is likewise carried by the casing head d. The tubing 3 has a connection with piping 4, which through the medium of a T 5 is associated with the pump a, and beyond the T such piping may lead to a sump, not shown, and likewise said piping has included in its length a stop cock 6. This stop cock is adapted to regulate the rate of flow of any fluid such as oil past the stop cock to the sump. It is also to be noted that the portion of the pipe 4 that leads to the sump is inclined downwardly

as shown in Figure 1. The T 5 permits communication both with the pump *a* and with piping 7 leading from such pump and T for conducting fluid to storage tanks, not shown; and such piping 7 has included in its length a stop cock 8. Piping 9 communicates with the pump *a* and with tubing 10 passed within the well hole and concentrically spaced from and within the tubing 10. 3. The connection within the pump *a* is such that fluid drawn through the piping 4 will be conducted in part within the pump *a*, through the piping 7, and likewise under pressure through the piping 9 and down the tubing 10. Also piping 11 is in connection with the air compressor *b* with such piping connected to piping 12 concentric within the tubing 10. The fluid elevating means *c* in the embodiment of the invention 20 shown in Figures 1 to 3 inclusive, includes a device 13 which comprises two annularly cupped members 14 and 15, received one within the other and slightly spaced apart, as shown at 16, the member 14 being provided with a central annular flange 17 which is screw-threaded internally as shown at 18 for screw-threaded connection with the lower end of the piping 12. The member 15 is provided with an annular flange 19 depending from the base of such member 15 and which flange is screw-threaded for engagement with the member 20 which is annular in formation, and which member 20 is provided at its periphery with two or 35 more radial flanges or wings 21 which are adapted to bear against the inner surface of a portion of the tubing 3, as shown at 22 to hold the jet means in operative position and against wobbling and which are 40 slidable in tube 3 to vary the position of member 15 relative to member 14 for controlling the size of the jet nozzle formed between the mouths of the cupped members. Also, the annular member 20 acts as a 45 spreader and provides a relatively constricted passage between itself and the tube 10 which assists in distributing to the fluid jet means, the fluid induced into the chamber 20^a. The lowermost end of the tubing 50 3 carries a valve 23 which is spaced below the lowermost end of the member 20 and forms within said tube a receiving chamber 20^a. The said valve includes a valve seat member 24 centrally bored as shown at 55 and formed with a tapered valve seat 26, and a ball or similar means 27 is adapted to normally rest on the tapered valve seat. Between the tubing 3 and the tubing 10, is a 60 spacer 28. This particular spacer acts to limit upward movement of means *e* and is not annular in formation. In other words it does not limit the flow of any fluid that might be passed upwardly through the tubing 3. The said means *e* is used for preventing the sanding up of the means *e* and

the said means *e* includes a member having a sleeve or annular portion 29 adapted for sliding engagement on the periphery of the tubing 10, and a flared or hollow conical portion 30 integrally formed with the annular portion 29, the extremity of which flared or hollow conical portion 30 is provided with an inner annular flange 31 and an outwardly projecting annular flange 32 inclined with respect to the flange 31. The upper end of the annulus 29 is beaded as shown at 33 so as to strengthen the same. It is to be noted that the spacing between the members 14 and 15 gradually diminishes in width from the central portion of such members to the rim of said members. The flanged extremity of the means *e* is adapted to rest when in one position over the device 13, it being noted that the flange 31 will close entrance within the annular cup of the member 14 and that the flange 32 would close the spacing between the members 14 and 15 with such flange likewise projecting beyond the periphery of the member 15. It is to be noted that the rim of the member 14 is below the rim of the member 15, hence the reason for inclining the flange 32. There is also another reason for inclining the flange 32 which will appear in the statement of the operation. 95

The operation of the device shown in Figs. 1 to 3, inclusive, will now be described before describing the modified forms. Assuming the pump *a* in operation and the compressor *b* likewise in operation with the said means *e* down in, say oil-bearing strata, that is to say, oil is within the casing 1 and around a portion at least of the tubing 3, oil will be pumped through the tube 9 down the tube 10 by the pump *a* under pressure, and the mouth 33' of such tube 10 terminates just above and likewise within the annular cup of the member 14 with the result that oil under pressure forced down the tube 10, has its direction of flow changed upon striking the member 14 to cause the oil to flow upwardly within the annular space between the tubings 10 and 3. While this is occurring compressed air is being forced at high velocity through the tubing 12 and through the space 16 between the members 14 and 15. The result will be that the means *e* will be lifted upwardly by the combined pressure of the oil and the air, the air striking the inclined flange, and a vacuum or at least a reduced pressure will be caused in the region of the member 13 and in the receiving chamber 20^a, with the result that any oil between the casing 1 and the tubing 3 will rush through the opening 25 in the valve 23 and lift the ball 27 from its seat. It is possible with this system to balance the column of oil flowing upwardly in the annular space between the tubings 3 and 10 so that no oil will be drawn through and past the valve 23. This can 125 130

be done by regulating the pump *a* and compressor *b*. It is possible to get such a balance that the pump *a* and the compressor *b* just keep the fluid, such as oil, flowing down through the tubing 10 and upwardly between the tubes 10 and 3 and through piping 4 communicating with such annular space between such tubings and into the pump. When such a nice balance has been reached it is evident that the slightest increase in the rate of flow or in the flow of the compressed air will immediately cause the valve 23 to open and permit any fluid such as oil within the casing to flow past the valve and up with the moving fluid being pumped. This oil drawn past the valve oftentimes contains sand and the heavier oil will pass through the pipe 4 through the T 5 and into the pump *a*, hence into the pipe 7 to a reservoir, the discharge of such surplus oil being regulated by the stop cock 8, while that portion of the surplus oil which contains sand being heavier, will be directed to the oil sump, the stop cock 6 in such pipe leading to the oil sump being regulated so as to cause a back pressure on the flowing oil. This method will effectively take care of the sand in the oil and help to remove such sand from the oil. When the pump *a* and the compressor *b* have stopped operation, the pressure against the means *e* is immediately relieved and the same will drop and cover the means *c* with the result that the heavy column of oil, which weighs a considerable amount, will remain within the tubing 3 being held within such tube by the valve 23, and any sand in such column of oil would naturally settle toward the bottom. The means *e*, however, prevents the sanding up of the device 13 so that the moment the pump *a* and the compressor *b* commence operation the sand that has settled is immediately displaced from its position, and as a consequence the sanding up of the device is impossible of accomplishment. It is evident from the device just described that I have provided a combined liquid pressure lift and air lift.

In Fig. 1 I have shown at 34 an annular member 35 attached to the inner surface of the casing 2 and just above the zone of the means *c* and *e*, the said member 35 being provided with a beveled face 36 which is inclined. The tubing 3 also carries an annular member 37 provided with a beveled face 38 which is adapted to cooperate with the beveled face 36 of the member 35. Connected to the annular member 37 are rods 39 and 40 and which rods extend upwardly to the surface of the well. It is intended that the two members 37 and 35 should so cooperate as to seal the annular space, existing between the casing 2 and the tubing 3. This construction will prevent oil within the casing from passing upwardly into the annular space between the casing 2 and the tubing 3 and will not provide any outlet for oil except past the valve 23. The tubing 3 might be cut off above the members 35 and 37 and not extend upwardly to the casing head *d*. A pipe 4 would then communicate with the interior of the casing 2 only, and any oil lifted past the means *c* would be received within such casing 2. The rods 39 and 40 would provide a ready means for lifting the tubing 3 from the well hole when desired, as it would be of short length and not very heavy. This method would likewise save tubing, as long connected strings thereof would be unnecessary.

Referring to Figures 4 to 7 inclusive, the form of the invention shown in Figure 4 does not differ essentially from the device shown in Figure 2, save and except that the air lift principle of the invention is not utilized, and only the annular cup-shaped member 15 is used. The other elements remain the same and the means *e* in place of having the two flanges 31 and 32 has a portion of its extremity bent inwardly as shown at 41 so as to fit within a portion of the member 15. The valve 23 is the same as before and in the application of the form of the device shown in Figure 4 oil or other fluid is pumped by the pump *a* down the tubing 10, and has its direction of flow changed by the member 15 so as to cause the oil to flow upwardly within the tubing 3.

The form of the device shown in Figure 5 includes the elements just shown for Figure 4 and in addition has a slightly modified form of air lift. The air compressor *b* would be the same as before and the pipe 12 would be received in the annular space between the casing 2 and the tubing 3, as shown at 42. The tubing 3 would not terminate adjacent the valve 23, as is the case of that form of the device shown in Figure 2, but would extend slightly below the base of such valve 23. The inner surface of the tubing 3 adjacent its lowermost mouth is internally screw-threaded as shown at 43, and screw-threaded upon such threads is a member 44. This member is annular in form, and provided with a plurality of transverse openings 45. The pipe 12 has a portion thereof fitted within the annular opening 46 of such member 44, and carried by the top of such member 44 and in direct communication with the annular opening is a valve 47 which includes a valve cage 48 secured to the member 44, as shown at 49, and a ball 50 seated within said cage. In the use of the device shown in Figure 5 oil to be lifted would flow through the openings 45 of the member 44 and past the valve 23. Air under pressure would lift the ball 50 and tend to produce an air lift in any oil passed through the openings 45 and likewise past the valve 23.

The operation, it will be seen, will be practically the same as that shown for the device in Figure 2. The ball 50 prevents a sanding up of the air lift pipe.

5 The space between the valve 23 and the member 44 provides an air chamber, with the result that practically no increased velocity of oil through the tube 10 to lift the column of oil within the tube 3, is required 10 when the compressor is in operation and forcing air past the valve 47 and into the said air chamber.

In Figure 7, I have shown on an enlarged scale means for sealing off the space between 15 the casing 2 and the tubing 3, and likewise providing a ready means for supporting a section of such tubing 3 where it does not extend the entire length of the casing 2 to the casing head *d*. This service is designated as *g* and does not differ essentially from the form shown in Figure 1 at 35 and 37. In this case, however, an annular wedge-shaped member 51 is secured to the tubing 3 and secured to the pipe 12 is an annular 20 wedge-shaped member 52 formed of sections with packing means 53 between certain of the sections. Other rod or rods 54 are likewise passed through and secured to the wedge-shaped member 52 so that when the 25 two wedge-shaped members 51 and 52 cooperate a section of the tubing 3 may be securely held in a definite location within the casing 2. The means *g* also effectively seals the space between the casing 2 and the tubing 3, so that any oil within such 30 space and below such means in order to escape would have to move upwardly past the valve 23 into the column of moving fluid so that the oil would be lifted to the 35 surface.

It is obvious that various changes and modifications may be made in carrying out 40 various features of the invention, in departure from the particular showing of the drawings, without departing from the true 45 spirit of the invention.

Having thus disclosed my invention, I claim and desire to secure by Letters Patent:

50 1. An apparatus of the class described including a delivery tube, fluid jet means disposed within the said tube, and means actuated by the pressure of fluid issuing from the jet to prevent the discharge orifice of said fluid jet means from becoming fouled.

55 2. An apparatus of the class described including a delivery tube, fluid jet means disposed within the said tube, automatically shiftable means mounted within the delivery tube and actuated by the pressure of fluid issuing from the jet to prevent the discharge orifice of said fluid jet means from becoming fouled.

60 3. An apparatus of the class described including a delivery tube, a tube within the delivery tube for supplying fluid under pres-

sure, a fluid jet at the discharge end of the last named tube, and means shiftably mounted on the last named tube and cooperating with the fluid jet means to prevent the same from becoming fouled.

70 4. An apparatus of the class described including a delivery tube, a valve seat member mounted in the tube, a ball valve cooperating with said ball seat, a cylindrical member spaced from the sides of the tube and disposed above said ball valve and providing a relatively constricted passage between its outer side and the tube, a portion of a fluid jet carried by said member, and a tube 75 for supplying fluid under pressure into said jet member.

80 5. An apparatus of the class described including a delivery tube, a valve seat member mounted in the tube, a valve cooperating with said seat, a cylindrical member spaced from the sides of the tube and disposed above said valve and providing a relatively constricted passage between its outer 85 side and the tube, a portion of a fluid jet carried by said member, and a tube for supplying fluid under pressure into said jet member.

90 6. An apparatus of the class described including a delivery tube having a substantially closed valved end and fluid jet means spaced from said end to provide a receiving 95 chamber, said jet means comprising cup-shaped members arranged one within the other and spaced apart, means for supplying fluid into the inner cup whereby its impingement thereagainst will change the direction of flow of the fluid, and means for supplying fluid under pressure into the space between said members and whereby the direction of flow thereof is changed thereby producing a vacuum in the receiving 100 chamber to open said valve.

105 7. Means of the character disclosed, including means for conducting a fluid to a given zone, and means at such zone for changing the path of movement of any fluid so conducted, said last named means comprising an annular cupped member; there being a second annular cup member below the first cup member and spaced therefrom, and means for discharging fluid under pressure into said second cup thereby providing a piston for lifting the first mentioned fluid.

110 8. Means of the character disclosed, including means for conducting a fluid to a given zone, and means at such zone for changing the path of movement of any fluid so conducted, said last named means comprising an annular cupped member; there being a second annular cup member below the first cup member and spaced therefrom, and means communicating with the space between said first and second cup members for conducting fluid under pressure to such space, and discharging it at the mouth of 115 120 125 130

- the cup whereby a piston for lifting the first mentioned fluid is provided.
9. A pump of the class described including a delivery tube, fluid jet means located within said tube and comprising cup members arranged one within the other and spaced apart, a pipe for supplying fluid under pressure connected with the inner cup and adapted to discharge between said cups, the outer cup being adjustably mounted in said tube for movement toward and away from the inner cup whereby a nozzle is formed between said cups at the mouth thereof, the adjustable cup being adapted to vary the size of the nozzle, and means for supporting said adjustable cup within the tube.
10. A pump of the class described including a delivery tube, fluid jet means located within said tube and comprising cup members arranged one within the other and spaced apart, a pipe for supplying fluid under pressure connected with the inner cup and adapted to discharge between said cups, the outer cup being adjustably mounted in said tube for movement toward and away from the inner cup whereby a nozzle is formed between said cups at the mouth thereof, the adjustable cup being adapted to vary the size of the nozzle, and means for supporting said adjustable cup within the tube, said means comprising tube engaging wings whereby the adjustable cup is held by friction within the tube.
11. A pump of the class described including a delivery tube, fluid jet means located within said tube and comprising cup members arranged one within the other and spaced apart, a pipe for supplying fluid under pressure connected with the inner cup and adapted to discharge between said cups, the outer cup being adjustably mounted in said tube for movement toward and away from the inner cup whereby a nozzle is formed between said cups at the mouth thereof, the adjustable cup being adapted to vary the size of the nozzle, means for supporting said adjustable cup within the tube, a pipe for discharging fluid into the inner cup whereby the impingement of the fluid against the cup operates to change the direction of flow of the fluid, the fluid jet operating as a piston for lifting the fluid discharged within the inner cup.
12. A pump of the class described including a delivery tube, fluid jet means located within said tube and adapted to discharge upwardly therein to provide lifting means for elevating the liquid to be pumped, and means for closing said jet means to protect it against sanding.
13. A pump of the class described including a delivery tube, fluid jet means located within said tube and adapted to discharge upwardly therein to provide lifting means for elevating the liquid to be pumped, and means for closing said jet means to protect it against sanding, said protecting means being automatically opened on the ejection of fluid through said jet means.
14. A pump of the class described including a delivery tube having a substantially closed valved end, fluid jet means spaced from said valved end to form a receiving chamber, said jet means comprising two cup-shaped members arranged one within the other and spaced apart, a compressed air pipe discharging into the space between said cups, a fluid supply pipe discharging into the inner cup whereby the compressed air operates to lift the fluid so supplied, said jet means forming a vacuum in the receiving chamber whereby the valve is opened to permit the inlet of the fluid to be lifted or pumped.
15. A pump of the class described including a delivery tube having a substantially closed valved end, fluid jet means spaced from said valved end to form a receiving chamber, said jet means comprising two cup-shaped members arranged one within the other and spaced apart, a compressed air pipe discharging into the space between said cups, a fluid supply pipe discharging into the inner cup whereby the compressed air operates to lift the fluid so supplied, said jet means forming a vacuum in the receiving chamber whereby the valve is opened to permit the inlet of the fluid to be lifted or pumped, means slidably mounted on said fluid supply pipe to close the space between said cups to protect it against sanding, said sliding means being opened by the operation of the jet when in action and closed by gravity.

In testimony whereof, I have signed my name to this specification.

CHARLES O. HASKELL.
